CONFECTION DISPENSING AND CONTAINER
COVERING APPARATUS

Henry W. Grau, Louisa, Va.

Application February 21, 1944, Serial No. 523,316

12 Claims. (Cl. 226—75)

1

The invention relates to new and useful improvements in confection dispensing and container cover applying apparatus.

An important object of my invention is the provision of a device adapted to fill fibre containers with ice cream or other semiliquid material, and also adapted for the disposing and seating of covers upon the containers. It will be observed that the present application incorporates improvements and new features over those disclosed in my Patent #2,278,923, issued April 7, 1942.

Another object of my invention is the provision of a confection dispensing apparatus wherein an empty receptacle is manually disposed below the discharge orifice of a dispensing hopper, and a filled receptacle is positioned below a cover applying mechanism operated in conjunction with the dispensing apparatus so that one of the receptacles may be filled and the other capped by a single operating cycle of the device.

Another object of my invention is the provision for the interchange of dimensional set-ups for operating with different sizes and types of containers and covers. A further object includes the provision of means for synchronizing actions of the cover applying mechanism, the dispensing mechanism, and the movement of a foot pedal, in relation to the quantity dispensed.

Another object of my invention is an improvement in the valve mechanism over that shown in my prior Patent #2,278,923.

Still another object of my invention is to provide a machine for filling containers by means of a dispensing pump, and disposing and seating covers upon containers by the actions of a foot pedal assembly by which one container is filled and a cover is seated upon another container by the downward movement of the foot pedal, and in which, the dispensing pump is recharged and a cover is disposed in position for capping or seating by the return movement of the foot pedal.

Another object of my invention is to provide a machine to perform the purposes set forth with energy supplied by a reciprocating foot pedal-actuated rod assembly, the assembly being supplied with a reciprocating force especially designed for the needs of the reciprocating movement.

Other objects of the invention, which includes the provision of a novel structural design and the use of materials permitting light weight reciprocating parts, as well as the utilizing of standard dimensional material stocks, will be apparent during the following description and claims.

2

In the drawings, forming a part of the specification, and wherein like numerals are employed to designate like parts throughout the same:

Fig. 1 is a combined, elevation of the hopper-cylinder assembly and a partial transverse section of the table.

Fig. 2 is a vertical section taken on line 2—2 of Fig. 5, showing dispensing pump and valve assembly.

Fig. 3 is a top plan view of the dispensing valve and supporting spring per se.

Fig. 4 is an end elevation with parts broken away of a confection filling and capping apparatus embodying my invention.

Fig. 5 is a top plan view of Fig. 4 with the hopper 2 cut away, showing operating elements of the dispensing pump and the cover disposer.

Fig. 6 is a horizontal sectional view on line 6—6 of Fig. 4 showing the roller guides.

Fig. 7 is a partial vertical section taken on line 7—7 of Fig. 4 showing the pedal arm guide.

Fig. 8 is a side elevation of the cover disposer.

Fig. 9 is a side elevation of the cover seating plunger disc.

Fig. 10 is a side elevation of the cover seating plunger stem.

Fig. 11 is a side elevation of the disc retaining spring.

Fig. 12 is a partial plan view of the cover plunger and disposer operating bracket as shown in Fig. 8.

Fig. 13 is a top plan view of the cover disposer.

Fig. 27 is a vertical sectional view of a container receptacle.

Fig. 28 is a vertical sectional view similar to Figure 27 in which the containers are of a larger size than those in Figure 27.

Fig. 29 is a front elevation of the complete machine.

In the accompanying drawings, wherein for the

purpose of illustration, is shown a preferred embodiment of my invention, the numeral 20 designates a table having a flat horizontally disposed top supported by upright leg members 72. The table is adapted to support the various operating parts of my device and is, therefore, of a height adapted to best position the operating parts within easy reach of the operator. Generally speaking the vertical supports 72 should be of sufficient length to position the table top at a level with or slightly above the waist of the operator, and these legs are rectangular in shape so as to accommodate the supporting of operating mechanisms of the foot pedal-actuating rod assembly. The table may be constructed of any suitable material, however, light weight angle iron has been found to be highly satisfactory in that a strong table that is light in weight and readily transportable is obtained. In order that a four point contact may be had with the supporting surface, the lower ends of the supporting legs are provided with feet by turning the web portion of the cross members into knobs extending downwardly as at 73.

The invention contemplates, in part, the provision of a confection machine which fills fibre containers with a semiliquid such as ice cream, and disposes and seats covers upon the filled containers by a foot operated pedal 68, thereby permitting the operator's hands to be free to handle the containers for receiving the ice cream and covers. Another purpose is to selectively control the quantity of confection dispensed as would be accommodated by various sizes of containers, this being accomplished by varying the length of movement of the actuating rod assembly.

The actuating rod assembly consists of the vertical reciprocating rod 44, to which is attached the foot pedal rod 64. These steel tubes 44 and 64 are of sufficient strength to afford the maximum needed stiffness with minimum weight. The foot pedal rod 64 is attached to a bracket 92, by means of the tie member 66.

In contemplating the operation of the machine it is evidently necessary that the actuator rod 44-42 that operates the dispensing pump, and the cover disposer and plunger, should reciprocate freely, with little friction, and little or no play or looseness of the composite rod 44-42 in its supports, so that accuracy in the quantity dispensed, and definite movement of the cover plunger may be attained. This is accomplished by providing the actuator rod 44 with two sets of three adjustable roller guides (see Fig. 6), there being a similar lower set of roller guides (not shown) attached to the bracket 60 (see Fig. 4). The roller guides are mounted on spindles, supported by two brackets 60 and 61, attached to the supporting legs and extending rearwardly beyond the table. These brackets 60, 61 are provided with two pairs of holes for receiving the spindles, one hole of each being oblong in shape, permitting the adjustment both laterally along the spindles and longitudinally along the brackets by the nuts on the ends of the spindles.

The pedal rod 64 extends across the full width of the table and is provided with a flat end 68 to form a treadle which projects beyond the legs in a manner to be easily accessible to the foot of the operator standing in front of the table. The guide 70 is bolted to the adjacent leg 72 and the pedal rod is received thereby in a manner to be guided in a vertical movement parallel to the actuator rod, as shown in Fig. 7.

The operating technique of a dispensing mechanism for controlling the flow of a semiliquid such as ice cream, presents several problems that must be taken into consideration for successful operation. Frequently, ice cream contains flavors having lumps of fruit or small particles of nuts or other ingredients. Also, a semiliquid has a tendency to hold a form as molded, for instance, the ice cream being expelled through the valve opening around the valve 30 (see Fig. 2) will tend to extrude in a tubular form. Experience has shown that if this should flow direct into a container, an air cavity will form within the body of the filled contents. Further, consideration must be given to design in respect to cleaning and inspecting as required by health authorities. The purport of design to this end will be shown.

The dispensing hopper-pump assembly Fig. 1, is held in position by a supporting arm 8, which is provided at its outer end with a clamp 6, which connects with the lower cylindrical portion 4 of the hopper and at its inner end with a sleeve clamp 10, which receives the rod 12 attached to the supporting frame formed by top 80 and legs 72. The clamp 11 may be used to set the hopper at a selected distance above the table top 80.

The hopper-pump assembly consists of a funnel shaped hopper 2 the lower end of which terminates in a depending cylindrical portion 4, having a straight circular surface through its full length and is provided with a pivoted spring stirrup 40 for clamping to the bottom of the cylinder 4, the dispensing valve assembly.

An extension rod 42, with two arms 46 and 112 horizontally extending over the table, is clamped to the actuator rod 44 by the telescopic clamp 47. The clamp 47 is formed by splitting the wall of the upper end of the actuator rod 44 and providing it with two lugs, one with a thread to receive the hand screw 49. The upper horizontal arm 46, extending over the center of the hopper is provided with a bearing 43, for receiving the piston rod 22 and the rod 22 is held in the bearing by pin 41.

The piston rod 22, is attached to the piston through a slide bearing 24, supported by the bail 26 on the piston 14. A valve 28 is attached to the end of the piston rod, and seats upon the upper edge of the valve seat insert 20 and is operated by the action of the piston rod. The pressure of the valve 28 against the edge of the valve seat 20 offers a shearing contact which aids in separating lumpy particles found in ice cream flavors. It will be obvious that by removing the valve seat insert 20, the valve 28 and rod 22 may be removed for examination.

The lower end of the cylindrical portion 4 is provided with a cylinder head 31, having an opening 32, the lower edge of which forms a seat for the hemispherical valve 30. This valve is suspendingly held against the seat 32 by the valve spring 34 which is retained in an annular recess in the upper face of the cylinder head 31. The upper end of an L-shaped nozzle 36 which is fitted against the lower face of the cylinder head 31 is circular in shape which allows the confection passage around the valve 30 and the horizontal portion has a smaller diameter than that of the upper end so that the confection will be expelled in a solid stream after taking a tubular form when passing around the valve 30. The delivery of the confection through orifice 38 at a point removed from the center of the cylinder 4, prevents dripping caused by the condensation on the hopper, from falling into the containers.

It will be observed that by removing the plug 5 in the end of the nozzle 36, all inside surfaces will be visible for inspection.

The horizontally extending arm 112 (see Figs. 4 and 8), from the extension rod 42, is provided on its outer end with a cover seating plunger means generally indicated at 110, that has a threaded holder rod 142, which fits the threaded bearing 113, attached to the end of the horizontal arm 112. The stem 144 (see Fig. 9) of the plunger disc 140 is slidably received in the end of the plunger holder 142 and is retained by the retaining spring 146 which fits the groove in the top of the stem 144 through the slot in the wall of the plunger holder 142. This detaching feature permits the interchange of various sized plungers.

The structure of the cover positioning means disposer (see Figs. 8 and 13) includes mechanism for removing fibre discs or covers individually from the bottom of a stack held in the magazine 132, and placing them in a position over a container 108 where they are detained.

In a manually operated apparatus it is very important that the reciprocating parts are as light in weight as practical to assure smooth, positive movements. Also, in such apparatus, in which the operator employs his hands to manipulate the containers to the dispensing nozzle 36, and from there to the cover disposer, it is necessary that the simultaneous operations are such that one container will be filled and another will be capped by the same movement of the actuator, and necessarily in this case by the initial or downward movement. Consequently the second or returning movement of the actuator rod must recharge the dispensing pump and simultaneously dispose a cover disc in position to be seated upon the succeeding container. A motion study of the operations described, proves this arrangement to be most desirable for efficient operation.

A departure from the usual custom in the construction of a cover disposer is that in the usual case, castings of various weights are usually employed, necessitating considerable machining in order to obtain smooth surfaces and close dimensions, whereas instead, in the present case, the structure of the cover disposer incorporates several smooth plates, shaped and fitted by shearing, stamping or otherwise cutting, and bolted to a base with assembly bolts. Referring to Fig. 8, it will be noted that the three plates 100, 102, and 104 are similar in outside outline so that they will coincide when placed one upon the other. The base plate 104 is provided with a circular opening 106 near the front end, in diameter slightly larger than a cover, and having a channel 166 (see Fig. 15), extending centrally towards the rear end. This channel acts as a guide for a shuttle shown in Fig. 25. The spacer 102 separates the top plate 100 from the base plate 104 and is of a thickness slightly greater than the thickness of a cover disc. When assembled, the semicircular portion 153 of the opening 102 in the front end of the spacer plate 102 coincides with a similar portion in the opening 106 in the base plate 104 and the curved portion in the rear coincides with a similar portion of the opening 150 below the cover magazine 132 and in the top plate 100. The narrow opening 160 between the rear ends of the spacer plate 102 allows the passage of the shuttle plate 174.

The top plate assembly Fig. 14 of the cover

disposer is of a thickness sufficient to afford the needed rigidity and this is true of the base plate. The assembly is made of three principal parts 100, 102 and 104 welded or otherwise assembled, and has several functions. The front end of the plate 100 is provided with an opening 106a which is slightly smaller in diameter than the coinciding opening 106 in the base plate 104, and affords a passage for the cover plunger 140. The edge 153 of the spacer plate 102 overlaps the opening 106 in the base plate and thus serves as a retaining flange for the cover disc. The open cylindrically shaped cover magazine 132 is attached in the opening 150 toward the rear of the top plate, and is spaced a short distance from the front opening 106a, so that the lower end of the magazine is flush with the bottom surface of plate 100. The top portion of the magazine cylinder 132 is provided with two upright posts 130 which have two horizontal holes near their ends. These holes form pivot bearings for the bell crank shown in Fig. 20.

The bell crank 122, 128, 124, 134, which gives horizontal reciprocating motion to the shuttle 137 of Figs. 25 and 26, is U-shaped with the two leg ends 128 terminating inwardly, so as to be pivotally received in the holes in the posts 130 attached to the cylinder 132. The loop portion 134 of the bellcrank passes below the base plate 104 and between two lugs 136 on the shuttle 137. The other end 122 of the bellcrank which is connected to the operating rod 116 is also formed in a U-shape, with its leg ends joined to legs 124, substantially at right angles to the leg ends 128.

The shuttle 137, Figs. 25 and 26, consists of an assembly of parts held together with assembly bolts 184. The pusher plate 174 is somewhat wider than the channel 166 in the lower plate 104, and of a thickness substantially the same as that of a cover disc. This plate 174 has an end recess corresponding nearly to that of a peripheral portion of a cover and is provided with two pressed counter sunk holes 189-189 for receiving two assembly bolts 184. It is of a length to extend across the opening 150 of the magazine. The guide bar 176 projects forward past the end of the pusher plate 174. This bar 176 is slightly narrower than the channel 166 in the base plate 104 in which it slides, and has practically the same thickness as the plate 104. The counter sunk portion of the pusher plate 174 interlocks with the countersinks 189 of the guide bar 176. The stay plate 178 is substantially the same width and thickness as the pusher plate 174 and shorter. Two lugs 136 are provided each of which consists of a square bar provided with a hole through its center with dimensions that will be obvious later. The lugs 136-136 fit below the stay plate 178 and the assembly is held together with two assembly bolts 184-184 as shown in cross section, Fig. 25. The two holes are spaced a distance apart so that the two lugs will accommodate the lower portion 134 of the bellcrank with little clearance. The length of the lugs 136-136 is slightly longer than the height of the segment of the arc made by the movement of the bell crank.

From the foregoing, it will be plain that when the shuttle 137 is in a rearward position, there will be a passage for a cover disc through the magazine 132, then forward between the base plate 104 and the top plate 100 and between the straight sides of the spacer plate 102 to the circular opening 106 in the base plate, and that

the forward movement of the shuttle 137 will cause the individual movement of the cover discs accordingly.

In order to retain the cover disc, after it is positioned under the cover plunger 140, I provide a retainer spring 154, that attaches under the assembly bolt and lockwasher 156, by the eye turned in the end. The other end of the retainer spring 154 is turned downwardly at right angles to the surface of the top plate 100, and through a hole 152 in same. The hole coincides with the two recesses 164, one in the spacer plate 102 and the other in the base plate 104, and permits the inward tension of the retainer spring 154 to contact the edge of the cover disc.

In order that the cover will enter the top of a container 198, positioned below the cover plunger 140 in exact register, I provide two plates 170 (see Fig. 15), each having guide fingers 172, which attach below the opening 106 in the base plate 104 by the four assembly bolts.

The supporting base 96, of the cover disposer is attached to the table top 80 by a slip head bolt 97. The base 96 consists of a steel plate shaped so that its extremities are turned upward to form supporting legs with their ends turned inwardly forming benches on either side, and to which are attached two of the assembly bolts. The forward edge of the bottom portion of the base 96 is provided with vertical flanges 148 forming a V, which help guide the containers to position in exact alinement with the plunger 140.

The cover disposer, being operated by the actuator rod-pedal assembly, is provided with a connecting means which, while simple in construction, is purposely designed to accomplish several operating functions. As previously mentioned, the necessity of having the cover discs move forward to the position under the cover plunger 140, by the downward movement of the foot pedal 68, the bell crank is so connected that its short end 122 is positioned forward in respect to the pivots atop the magazine. This end having a round horizontal section is provided with a split bearing 126 (see Fig. 8), held in place on the crank by two clamp nuts on the lower end of the operating rod 116, which rod passes through a slide bearing on the upper end of bracket 114. The bearing permits a loosely sliding fit, and the bracket 114 is detachably connected to the horizontal arm 112, previously described.

In the operation of the bellcrank 122-124-134, a short arc is described by the bearing member 128, and since the reciprocation of the slide bearing on the end of the bracket 114 is in a straight vertical line, oscillation of the operating rod 116 caused by arcuate movement of bearing member 126, is permitted. The spacer spring 120, cushions the downward pressure of the bracket. The upper spring 118, acts as a cushion for the pressure occasioned by upward movement. The space between the two springs 118 and 120 is adjusted by means of the two lock nuts 138 on the upper end of the operating rod 116, as will be explained later.

In the operation of the machine, a movement in each vertical direction of the foot pedal-actuating rod assembly completes one cycle of operation. The movements in each direction have different functions. The downward movement, expels the confection from the nozzle 36 through the downward action of the pump piston 14. The downward movement also seats the covers upon the containers and moves the shuttle to the position back of a cover at the bottom of a stack of

covers in the magazine. The upward movement of the foot treadle and associated parts raises the piston 14, recharging the pump cylinder 4, and also moves the shuttle 137 forward, disposing a cover under the cover plunger 140.

The energy necessary to complete an operating cycle is supplied by pressing the foot pedal. It is obvious that this is a single direction movement and forms one half cycle of operation. 10 Therefore, part of the energy supplied to the first half cycle must be stored up for operating the second half cycle. The force required to operate the actuating rod is fairly constant throughout the length of its movement. Therefore, in order 15 that the upward movement of the treadle may not depend wholly upon the tension of spring 74, which lessens or grows weaker as it closes, I provide an auxiliary spring actuating means 20 which comprises a bellcrank lever 84, the apex 25 86 of which is pivoted to the frame below the lowermost position reached by the bracket 92. The arm 82 of the bellcrank lever is connected to the framework of the table by the coil spring 76. The consequent leverage supplies a reciprocating force equal to the needs of the reciprocating movement.

The limits of the movement of the actuator rod 44 are determined by the stop 77 attached to the bottom of crossmember of the leg, and 30 the upper stop member 79, above the adjustable stop bolt 94 which contacts it on its upward movement. The stop bolt is vertically supported in a socket or bearing, attached to the side of the bracket 92 which is directly beneath the stop member 79.

In the operation of the machine the quantity dispensed depends upon the length of the dispensing pump stroke and is selectively determined by adjusting the length of the stop bolt 94. The length of the movement of the actuator rod 44-42 is necessarily longer than the movement required to operate the cover disposer, therefore, a space is provided between the spacer springs on the operating rod 116 of the cover disposer, to allow for the difference. The upper spring 118 is normally slightly compressed when the actuator rod 45 is in its uppermost position which is the normal idle position. When an adjustment is made so as to regulate or change the dispensing stroke, by the adjustment of the stop bolt 94, a corresponding adjustment is made with the locknuts 138 on the top of the cover disposer operating rod 116.

From the above description, it will be seen that the operating movements are as follows: The operator removes a container from a cup dispenser and holds it beneath the orifice 38 of dispensing nozzle 36 and presses on the foot pedal 68. With that movement the container will be filled and the shuttle 137 will move to a position back of the opening 106 in the cover magazine. As the pressure upon the foot pedal 68 is released the reciprocating rod assembly 44 and 42 will return to its original position completing the operating cycle. At the same time the operator releases the filled container held in his right hand and grasps the second. Simultaneously he grasps the filled container with his left hand and places it against the guide flanges on the cover disposer base beneath the cover plunger 140. During the upward reciprocating movement, the pump will be recharged and the shuttle 137 will push a cover disc to position beneath the cover plunger 140. As the operation is repeated the first con-

tainer will be capped and the second one will be filled.

It is to be understood that the form of my invention herewith shown and described, is to be taken as a preferred example of the same, and that various changes in size, shape and arrangement of parts may be resorted without departing from the spirit of my invention, or the scope of the appended claims.

I am aware that the present application incorporates some features revealed in my previous patent (2,279,923).

Improvements included in the present application relate to the actuator rod and roller guides, the dispensing pump valves; the cover disposer, the operating connections, and the arrangement of synchronized operating movements.

Having thus described my invention, I claim:

1. In a filling and capping machine the combination of a hopper, piston means to force semi-liquid material out of said hopper into a container, means to position a cover above a container and plunger means to seat a cover upon a container, said plunger and piston means being actuated simultaneously, such piston means being actuated to force the material out of said hopper and such plunger means being actuated to seat a cover upon a container by a common means moving in one direction, and such cover positioning means being actuated by movement of said common means in an opposite direction.

2. A dispensing nozzle for a filling machine comprising a receiving chamber that is substantially hemispherical in contour with the axis of the hemisphere extending vertically, a substantially horizontally extending tubular wall connected to said receiving chamber and a discharge orifice located in the lower portion of said tubular wall at a point remote from said hemispherical chamber, the diameter of said tubular wall being less than the diameter of said hemispherical chamber, said tubular wall terminating in an end opening, and a clean-out plug closing said opening.

3. A dispensing nozzle for a filling machine comprising a receiving chamber that is substantially hemispherical in contour with the axis of the hemisphere extending vertically, a substantially horizontally extending tubular wall connected to said receiving chamber and a discharge orifice located in said tubular wall at a point remote from said hemispherical chamber, the diameter of said tubular wall being less than the diameter of said hemispherical chamber, said tubular wall terminating in an end opening that is closed by a clean-out plug.

4. In a filling and capping machine the combination of a hopper, piston means to force semi-liquid material out of said hopper into a container, means to position a cover above a container and plunger means to seat a cover upon a container, said plunger and piston means being actuated simultaneously by a common means, said common means including a vertically extending rod, means connecting said plunger and piston means to said rod, said rod being embraced by adjustable roller guides whereby exact movement of the plunger and piston means is obtained.

5. In a machine for filling containers with a semi-liquid material such as ice cream or the like, a hopper, a feed cylinder depending from said hopper, the lower end of said feed cylinder having a head removably secured thereto and a dis-

charge nozzle removably secured to said head, said discharge nozzle comprising a receiving chamber that is substantially hemispherical in contour with the axis of the hemisphere extending vertically, a substantially horizontally extending tubular wall connected to said receiving chamber and a discharge orifice located in said tubular wall at a point remote from said hemispherical chamber, the diameter of said tubular wall being less than the diameter of said hemispherical chamber, said tubular wall terminating in an end opening that is closed by a clean-out plug, said cylinder having a piston therein and a piston rod connected to said piston by means of a bail, whereby said rod can move with respect to piston, the piston having an opening therein adapted to be closed by the end of said piston rod and said head having a one-way valve therein permitting said material to pass into said nozzle and be dispensed therefrom by the action of said piston.

6. In a machine for filling containers with a semi-liquid material such as ice cream or the like, a hopper, a feed cylinder depending from said hopper, the lower end of said feed cylinder having a head secured thereto and a discharge nozzle secured to said head, said discharge nozzle comprising a receiving chamber that is substantially hemispherical in contour with the axis of the hemisphere extending vertically, a substantially horizontally extending tubular wall connected to said receiving chamber and a discharge orifice located in said tubular wall at a point remote from said hemispherical chamber, the diameter of said tubular wall being less than the diameter of said hemispherical chamber, said tubular wall terminating in an end opening that is closed by a clean-out plug, said cylinder having a piston therein and a piston rod connected to said piston by means of a bail, whereby said rod can move with respect to piston, the piston having an opening therein adapted to be closed by the end of said piston rod and said head having a one-way valve therein permitting said material to pass into said nozzle and be dispensed therefrom by the action of said piston, said valve being substantially hemispherical in shape with its curved surface disposed upwardly.

7. In a confection filling machine, a support, a hopper arranged above the support and having a depending cylindrical portion open at its upper and lower ends, a piston operating within the cylindrical portion, valves for controlling the flow of the confection from the hopper including a lower valve seating upwardly against the cylindrical portion, and an upper valve operatively attached to a piston operating rod and seating downwardly against the said piston, a bail connected to said piston, a bearing supported by said bail, said rod extending through said bearing and said valve being movable between said piston and said bearing to engage said bearing, an actuator means mounted for vertical reciprocation relative to the support and including a depending tie element connecting with the said piston rod whereby the upward movement of the actuator opens the said upper valve and raises the said piston thereby recharging the cylinder, and the downward movement closes the upper valve and moves the piston downward thereby discharging the contents of the cylinder through the said lower valve.

8. In a confection filling machine, a support, a hopper arranged above the support and having

11

a depending cylindrical portion open at its upper and lower ends, a piston comprising an apertured disk operating within the cylindrical portion, an actuator mounted for vertical reciprocation relative to the support and including a depending tie element connecting with a piston operating rod, an adjustable stop means for restricting the stroke of the actuator means to within predetermined limits whereby such restriction will control the quantity of confection to be discharged from the cylinder, valves for controlling the flow of the confection from the hopper including a lower valve seating upwardly against the cylindrical portion, and an upper valve attached to the said piston rod, the said rod being connected to the piston through a slide bearing attached to the piston, and the said upper valve seating downwardly against a removable valve seat insert within the piston, whereby the removal of the said valve seat insert permits the removal of the said valve and piston rod.

9. In a confection filling machine, a support, a hopper arranged above the support and having a depending cylindrical portion open at its upper and lower ends, a piston comprising an apertured disk operating within the cylindrical portion, valves for controlling the flow of the confection from the hopper including a lower valve seating upwardly against the cylindrical portion, and an upper valve operatively attached to and seating downwardly against the said piston, an actuator means mounted for vertical reciprocation relative to the support and including a depending tie element connecting with the said piston, adjustable stop means for restricting the stroke of the actuator means to within predetermined limits thereby controlling the quantity of confection to be discharged from the cylinder, and the said actuator consisting in part of a rod mounted for vertical reciprocation between two sets of roller guides, each set being supported by two adjustable spindles, whereby adjustment is provided for varying the contact between each set of roller guides and the said rod.

10. In a confection filling machine, a support, a hopper arranged above the support and having a depending cylindrical portion open at its upper and lower ends, a piston comprising an apertured disk operating within the cylindrical portion, valves for controlling the flow of the confection from the hopper including an upper valve operatively attached to and seating downwardly against the said piston, an actuator means mounted for vertical reciprocation relative to the support and including a depending tie element connecting with the said piston and valve, spring means normally urging the actuator means to an elevated position for effecting the raising of the valve and piston thereby recharging the cylinder, and the said spring means including a bell crank lever pivoted to the support and hav-

12

ing one arm thereof linked to the said actuator means, a coil spring connected to the other arm of the lever and the support respectively, a treadle connected to said rod for moving the latter against the action of the spring, and a lower valve seating upwardly against a removable cylinder head, an L-shaped nozzle fitted to and held against the said cylinder head and around the said lower valve, whereby the operation of the said actuator will cause the confection to flow around the said lower valve and through the said nozzle and be expelled in a solid mass.

11. In a machine for dispensing material, a feed cylinder and a piston therein, said piston comprising a disk having a central opening the edge of which comprises a valve seat, a bail connected to said disk, a bearing supported by said bail, a piston rod extending through said bearing, said piston rod being movable with respect to said disk, a valve on the end of said piston rod extending through said bearing, said valve seating upon said seat when said piston rod is moved in one direction to close said opening and actuate said piston in said one direction and engaging said bearing to actuate said piston in the opposite direction when the piston rod is moved in said opposite direction, and a one-way valve closing the discharge end of said feed cylinder.

12. In a filling and capping machine the combination of a hopper, piston means to force semi-liquid material out of said hopper into a container, means to position a cover above a container and plunger means to seat a cover upon a container, said plunger and piston means being actuated simultaneously by a common means, said common means including a vertically extending rod, and means connecting said plunger and piston means to said rod.

HENRY W. GRAU.
